DIE CASTING MACHINE

William J. During, Syracuse, N. Y., assignor to
 Precision Casting Company, Inc., Syracuse,
 N. Y., a corporation of New York

Application November 22, 1937, Serial No. 175,871

2 Claims. (Cl. 22—69)

This invention relates to an improvement in a die casting machine in which a delivery nozzle is movable into and out of co-operative relation with the sprue opening or inlet port of a die. The invention relates more particularly to a die casting machine having a sectional die member with the sprue opening or inlet port thereof arranged in the plane of separation of the die sections and wherein at least one of said die sections is movable with respect to the other section for opening and closing the die.

In die casting machines having a die of the above mentioned type the delivery nozzle has usually been moved into direct contact with the die sections during the casting operations. The result has been that the nozzle tends to force the die sections apart due to the relatively high pressure exerted on the nozzle necessary to prevent leakage of the molten metal between the nozzle and wall of the inlet port. This separation of the die sections permits the molten metal to escape from the die cavity and is not only detrimental to casting results but is also dangerous to the operator.

The main object of this invention is to provide a die casting machine of the above mentioned class with pressure compensating means interposed between the delivery nozzle and the die, when the nozzle is in the casting position for opposing or absorbing the pressure produced on the nozzle during the casting operation whereby the die sections may be easily maintained in tight co-operative relation with each other during the ejection of the molten metal into the cavity of the die.

A more specific object of the invention is to provide a seat for the delivery nozzle of a die casting machine adapted to be engaged by said nozzle during the casting operation and which will conform to the general contour of the nozzle through out a cross sectional area thereof and thereby contribute to the length of life of the nozzle.

These and other objects pertaining to the structure and operation of my novel compensating device will more fully appear from the following description taken in conjunction with the accompanying drawing, wherein:

Figure 1 is a detail side elevation of a die casting machine embodying the various features of this invention.

Figure 2 is a longitudinal vertical sectional view of a ladle or pressure pot and the adjacent end portion of the die member associated therewith, taken substantially on line 2—2, Figure 3.

Figure 3 is a vertical sectional view through the die casting frame taken substantially on line 3—3, Figure 1 with the adjacent ends of the die sections and my novel pressure compensating element or nozzle plate associated therewith illustrated in elevation.

In order to illustrate my invention, I have shown a die casting machine having a ladle or pressure pot provided with a discharge or delivery nozzle and which is movable from a retracted position in a melting pot with the nozzle submerged in the molten metal contained in the melting pot to receive the metal therefrom, to an extended position with the nozzle in operative relation with the sprue opening of the die for ejecting the molten metal into the die cavity.

More specifically, the die casting machine comprises the usual frame or fire box 1 having a furnace chamber 2 therein. A cover plate 3 is secured by any suitable means to the upper face 20 of the frame 1 and has mounted thereon a suitable melting pot 4 adapted to extend downwardly from the plate 3 into the furnace chamber 2. A die member 5 is shown mounted on the machine frame, adjacent the forward end of the melting pot 4.

The die 5 is a sectional member having the lower section as 5', thereof mounted upon the frame 1 and which may be removably secured to said frame by any suitable means as bolt 6 whereby 30 said die section may be maintained in fixed predetermined relation with the melting pot 4 and frame 1. The other die section, as 5'', is mounted for movement into and out of engagement with the lower die section 5' for opening and closing 35 the die. Any suitable means may be connected with the die section 5'', as an operating member or carriage indicated at 7, for producing vertical movement of the die section 5'' with respect to the die section 5'. The die is provided with a sprue opening or inlet port 8 formed by slots or grooves 8' and 8'' in adjacent faces of the die sections 5' and 5'' respectively at the ends of said sections adjacent the melting pot 4, said inlet opening being in communication with the cavity 45 9 of the die.

The ladle or pressure pot 10, in this instance is of the goose neck type and is provided with a vertically disposed major portion 11 having a pressure chamber 12 therein. A spout or goose neck 50 13 extends from the lower end of the portion 11 and has secured to the outer forward end thereof a delivery nozzle 14 which is in communication with the pressure chamber 12.

A bracket 16 is secured by bolts 17 to the upper 55

portion of the delivery pot 10 to extend forwardly from the major portion 11 of the pot. The bracket 16 has secured to the forward end thereof a horizontally disposed shaft 18 which extends outwardly at either end from the bracket 16 through guide slots 19 provided in a pair of opposite vertically extending plates 20 which are made integral with or secured to the upper surface of the frame 1 at opposite sides of the melt-
10 ing pot 4 and near the forward end thereof.

The guide slots 19, in this instance, are each composed of a horizontal portion 19' disposed in a plane above the lower die section 5' and a vertical disposed portion 19'' which extends downwardly from the rear end of the horizontal portion 19' thereby forming the inverted L-shaped slot 19 for guiding the pressure pot from the casting position to the charging position and vice versa. In this instance, the width of each slot 19 is greater than the diameter of the adjacent ends of the shaft 18 so that a roller, not shown, may be rotatably mounted on each outer end of the shaft 18 and which is adapted to travel in a respective slot 19 to effect the easy movement 25 of the shaft through said slot.

The shaft 18 is moved through the slots 19 by means of a pair of rock arms 23, positioned at the outer sides of the plates 20. The arms 23 are journaled for pivotal movement on respective 30 shafts 24, said shafts being secured to the lower portion of the respective plates 20 near the forward end thereof so that when the shaft 18 is positioned in the forward portion of the guide slots 19 to bring the pressure pot into the casting position, the rock arms 23 will extend substantially vertically.

The rock arms 23 may be operated by any suitable means, as for instance, a cross head, not shown, slidably mounted upon a suitable guide 40 secured to a convenient portion of the machine, also not shown, the cross head being connected to the arms 23 by a pair of drive rods 26. Each rod 26 is pivotally secured at its rear end, as at 27, to the lower end of a corresponding rock arm 28, secured at the upper end thereof to a respective arm 23.

The upper ends of the rock arms 23 are each provided with an elongated slot 30 through which the outer ends of the shaft 18 extends. The 50 width of the slots 30, as shown, are greater than the diameter of the shaft 18 so as to receive therein rollers, not shown, rotatably mounted on the ends of the shaft 18. The rollers mounted on the ends of shaft 18 which travel in the slots 19 and 30 provided in the plates 20 and arms 23 may be maintained on the shaft by any suitable means as by collars 31 secured to respective ends of the shaft.

The pressure pot 10 is maintained against un-
60 duely rocking movement about the axis of the shaft 18 by means of a guide rod 32 which is secured to the rear portion of a bracket 16 and extends rearwardly therefrom with the rear end of said guide rod slidably mounted in a pivotal arm 33 secured to a rock shaft 34 mounted in a bracket 35 secured to the cover plate 3. The rock shaft 34 is provided with a passageway or duct 36 which extends from one of the outer ends thereof inwardly and then upwardly through the arm 33 into registration with a passageway or bore 37 provided in the guide rod 32 and which extends from the arm 33 to the forward end of the rod. The forward end of the passageway 37 is maintained in communication with the pressure chamber 12 of the pot 10 by a duct 38 provided

in the rear portion of the bracket 16, as shown in Figure 2, so that when the pressure pot is in the casting position, the fluid as air under pressure may be admitted through the shaft 34, passages 36 and 37, and duct 38 to the pressure chamber 12 for discharging the molten metal contained in said chamber through the delivery nozzle 14 into the die 5.

The passage 36 in the shaft 34 and arm 33 may be connected with any suitable source of 10 fluid pressure such as a pump, not shown, by a suitable conduit 39 which may or may not be provided with a suitable control valve, also not shown, for manually controlling the flow of fluid therethrough.

It will now be observed that when the pressure pot 10 is moved from the casting position as illustrated by full lines in Figure 2, to the charging position illustrated by broken lines in said figure, the nozzle 14 will be submerged in the molten metal contained in the melting pot 4 due to the pressure pot being rocked about the axis of shaft 18 during the vertical movement of said shaft in the guide slots 19 and to the pivotal action of the guide rod 32 about the axis of the shaft 34 as said guide rod is moved endwise through the arm 33. Similarly as the pressure pot 10 is moved from the charging position with the nozzle 14 submerged in the metal contained in the melting pot 4 to the casting position by the action of the arms 23 moving the shaft 18 along the guide slots 19, the nozzle 14 will be brought into operative alignment with the intake port 8 of the die 5 as the shaft approaches the horizontal portion 19' of the guide slot by the action of the 35 guide rod 32.

As the pressure pot is caused to continue its forward movement by the action of the arms 23 upon the shaft 18, the nozzle 14 will be brought into casting relation with port 8.

In order to compensate for the pressure exerted on the pressure pot by the arms 23 to maintain the nozzle 14 in seal tight contact with the die inlet opening, I have provided a nozzle plate 40 having a tapered aperture 41 provided therethrough which provides a seat for the outer or discharging end of the nozzle 14. The nozzle plate 40 is secured to the lower fixed die section 5' as by bolts 40', with the nozzle seat 41 in alignment with the inlet opening 8 of the die 5 50 when the die section 5'' is in contact with the die section 5'. In as much as the inlet opening 8 of the die and the nozzle seat 41 of the nozzle plate 40 are in substantially the plane of separation of the die sections 5' and 5'' the screws or 55 bolts 40' are all arranged below the horizontal plane passing through the inlet opening and nozzle seat. In order, therefore, that the upper portion of the nozzle plate 40 may be supported against springing outwardly by pressure exerted thereon during the ejection of the molten metal through the nozzle 14, into the die cavity 9 I have provided a pair of supporting blocks 42 which are connected by screws 43, or their equivalent, to the upper die section 5'' adjacent the vertical sides thereof and in position to extend over corresponding side portions of the upper end of the nozzle plate. These supporting blocks 42 have the inner adjacent vertical faces thereof recessed, as at 44, for the reception of the adjacent upper end portions of the nozzle plate. These recesses 44 are formed with the wall thereof facing the outer side of the supporting block tapered from the upper end downwardly and outwardly for engagement with the upper end 70 75

portion of the nozzle plate which is correspondingly tapered for wedging said upper end portion of the plate between the supporting blocks and the upper die section 5" when the die sections 5' and 5" are in casting relation with each other.

It will now be observed that in as much as the ends of the die sections 5' and 5" adjacent the melting pot 4 and nozzle plate 40 are in the same vertical plane the upper end portion 10 of the nozzle plate 40 will be maintained in contact with the upper die section 5" with sufficient pressure by the supporting blocks 42 to prevent passage of molten metal between the nozzle plate and the upper die section during the casting operation.

Furthermore it will be observed that in as much as the nozzle plate 40 is a fixed member and the pressure pot 10 has a definite path of movement produced by the co-action of the shaft 18 20 and the guide slots 19, the nozzle 14 will also have a definite relation with the seat 41 during the casting operation and therefore the end of the nozzle engaging said seat will not only have a fluid tight pressure fit with the seat, but will 25 also be maintained against excessive wear during the casting operation.

Although the construction and operation of the device shown and described are particularly simple and efficient, I do not wish to be limited to 30 the exact detail shown as various changes may be made therein without departing from the spirit of the invention as set forth in the appended claims.

I claim:

35 1. In a die casting machine having a die composed of sections with at least one of said sections movable toward and from another section to open and close the die, said die being

provided with an inlet port in the plane of separation of said sections, in combination, an apertured nozzle plate, means fixedly securing the nozzle plate to one of said die sections in sealing contact therewith and with the aperture in the plate in registration with the inlet port of the die, a delivery nozzle movable into pressure engagement with said plate in registration with said plate aperture when the die sections are in the closed position to discharge molten metal 10 through the plate aperture and die inlet port into the die cavity, and separate means connected with the second die section and releasably engagable with the nozzle plate when the die is closed to maintain said plate in sealing 15 contact with the latter die section during said discharging of the molten metal.

2. In a die casting machine having a delivery nozzle, a sectional die member having at least one section movable to open and close the die, 20 said die being provided with a sprue opening in the plane of separation of the sections, and means for producing relative movement of the die and nozzle to bring them into and out of casting relation with each other, in combination, an apertured nozzle plate interposed between the nozzle and the die member, and means securing the nozzle plate to the die member in sealed relation therewith when the die is closed independently of pressure produced on said plate by the 30 nozzle when said nozzle is in said casting relation with the die, said latter means including a holding element associated with one of the die sections adapted to be brought into and out of operative engagement with the nozzle plate during 35 the closing and opening of the die member.

WILLIAM J. DURING.
